UNITED STATES PATENT OFFICE.

STEWART CAIRNCROSS, OF GRAFTON, NORTH DAKOTA.

AERIAL MACHINE.

SPECIFICATION forming part of Letters Patent No. 432,860, dated July 22, 1890.

Application filed February 10, 1890. Serial No. 339,828. (No model.)

To all whom it may concern:

Be it known that I, STEWART CAIRNCROSS, residing at Grafton, in the county of Walsh and State of North Dakota, have invented 5 certain new and useful Improvements in Aerial Machines, of which the following is a specification.

My invention relates to that class of air-ships wherein suitable mechanism is connected to the gas-bag or balloon proper which serves to raise the machine and propel and steer the same when in the air.

My invention has for its object to construct an air-ship of this character which will be 15 light in weight but strongly built, and which can be quickly manipulated by the operator, so as to ascend or descend and to travel in any desired direction.

To this end my invention consists in providing a suitable frame to which the gas-bag is held by means of the usual netting, and to the lower face of such frame is disposed a shaft, upon the outer end of which is secured a propelling-wheel, which is operated by 25 means of intermediate gearing devices disposed at the junction of such balloon-frame, and a supporting frame or cage adapted to be suspended from the balloon-frame, such cage being always disposed in a vertical position.

It also consists in adjusting the balloon-frame and the propeller-wheel in relation to such depending frame or cage and connecting it therewith so that the said balloon-frame 35 and the propeller can be turned to any angle between one to ninety, so as to cause the propeller to rise up in the direction desired.

It further consists in adjusting the several parts of the machine in such a manner that 40 the same will normally raise a predetermined weight—*e. g.*, one hundred and twenty-five pounds—whereby when the operator steps into the cage his weight will serve to hold the ship from rising, necessitating his operating 45 the propeller-wheel to supply the power necessary to raise the difference of his weight and the normal capacity of the machine.

Finally, my invention consists in the novel arrangement and peculiar combination of 50 parts, all of which will hereinafter be fully described in the annexed specification, and particularly pointed out in the claims, refer-

ence being had to the accompanying drawings, in which—

Figure 1 is a side view of my improved aerial machine, the balloon proper and the propeller being disposed in a horizontal position to more clearly illustrate the relation of the parts. Fig. 2 is a front view of the same, the balloon-frame and propeller being shown in vertical position, parts being broken away. Fig. 3 is a rear view of the machine, the parts being in the position shown in Fig. 1. Fig. 4 is a detail view hereinafter referred to.

In the accompanying drawings, A indicates the main or balloon frame, which is constructed of any light material, preferably bamboo, formed in sections and jointed in any well-known manner, the under side of such frame being covered by a light glazed covering *a*, such as silesia.

B denotes a shaft disposed horizontally below the frame A, journaled in bearings *bb*, held upon the parallel members *a' a'* of the frame A, as most clearly shown in Fig. 2 of the drawings, the rear end of such shaft being also journaled in a transverse member *a²* of such frame. The front end of the shaft B is extended beyond the frame A and forms a bearing for the propeller-wheel D, which may 80 be of any well-known construction, being braced to said shaft to turn therewith.

In the rearward extension *a⁴* of the members *a' a'* are journaled short shafts *c c'*, arranged in the same horizontal plane, upon which is hung the supporting frame or cage E, which consists of the hangers *e e*, the upper ends of which are forked and supported from the shafts *c c'*, as shown, the lower ends of which are connected with and support the platform F, being braced therewith by the braces *f f*, a suitable screen *f'* being provided on said platform to form a frame or cage for the navigator. A transverse crank-shaft G is journaled in the hangers *e e* at a convenient height from the platform F, the cranks *g g* of which are connected by means of pitmen *H H* with foot-levers *I I*, pivoted in the platform F, the outer ends of the shaft G being provided with crank-handles *g' g'*, as shown. A sprocket-wheel J is mounted upon the shaft G, which communicates motion by means of the chain-belt K to a similar wheel mounted on the shaft *c'* at the upper end of

the cage E, the inner end of such shaft being provided with a bevel-gear L, which meshes with a bevel-gear M on the rear end of the propeller-shaft B. By the aforesaid construction it will be observed that the operator may turn the crank-shaft G by means of the crank-handles g', or in case he desires to rest his arms by means of the foot-levers I or in case of necessity he can operate the 10 crank-handles and the foot-levers at the same time, and thereby communicate motion to the propeller-wheel D. To prevent any undue friction on the shaft c', which might be caused by the weight of the hanger e of the frame E, which is supported therefrom, I provide that 15 part of the rear end of the member a' through which said shaft passes with a sleeve or hub 10, and from the transverse member a² projects a bracket S, provided with a hub 20, in 20 which is journaled the outer end of such shaft c'.

By reference to Fig. 4 of the drawings, which clearly shows the arrangement of the shaft c' and its supports, it will be observed 25 that I hang the supporting-bar e on the hubs 10 and 20, thereby placing all the strain of the said supporting-bar on the frame A and not on the shaft c'.

N denotes the gas-receptacle or balloon 30 proper, which is held on the top of the frame A by means of the netting usually employed, which normally is always inflated to the proper buoyancy, no matter whether the machine is at rest or is in operation.

O denotes the steering-vane, pivoted at o to the frame A at one side of the center of the said frame at the rear end thereof to swing horizontally, the front end of such vane being connected by means of the cords 40 which pass over suitably-arranged guide-rollers 30 and 40 on the frame A and guide-pulleys 50 and 60 on the hanger-frame E, the pulley 60 being provided with a handle 70 and disposed within easy reach of the navigator, so that he may readily operate the steering-vane, as the occasion may require.

P indicates a stay or guide rope connected at its ends with the front and rear edges of the frame A, said rope passing over a pulley 50 80, within easy reach of the navigator on the lower portion of one of the hanger-bars e, such rope being held to maintain its proper relation during the swinging motion of the frame A by means of a dolphin striker or 55 stick Q, secured at its upper end to the frame A, its lower end projected in advance of the guide-pulley 80 and connected to said rope, as shown.

To allow for the frame A being turned to 60 an almost vertical position, I form the rear part with a cut-away portion A², which admits of the easy manipulation of the operating mechanism.

The manner of operating my improved air- 65 ship is as follows: The machine, when on ground, has the frame A in the position shown in Fig. 2, being held to the ground by means

of suitable guy-ropes or in any other manner. The aeronaut then steps onto the platform, his weight serving to hold the machine 70 from ascending. The other means for holding it down are then released. The aeronaut then operates the crank-shaft G, which in turn will cause the propeller to revolve in a direction to cause the atmospheric pressure 75 to raise the machine from the ground. After the machine rises from the ground a height sufficient to clear objects the frame A is lowered toward a horizontal position; but in practice it is never lower than about fifteen to 80 twenty degrees, such movement being accomplished by turning the pulley 80, thereby turning down the frame on its pivots c' to the position desired. By adjusting the steering-vane in the manner before described the 85 operator can cause the machine to move in the direction desired.

By my improved construction it will be observed I have reduced the total weight of the machine, so that the same will be very light 90 and buoyant, and when the same has ascended to the height desired (such ascension being made vertically when at the start and diagonally upward and forward when traveling) the operator can at any time, by turning the 95 frame A to a vertical position and slowing the movement of the crank-shaft G, cause the machine to descend, thereby having the movement of the descent under ready control. Should, however, the downward movement of 100 the machine become too rapid in case the balloon should collapse, the operator can turn the frame A to a horizontal position, which, owing to its peculiar construction, would serve to act in the manner of a parachute and 105 quickly check the downward momentum of the machine.

It is manifest that instead of arranging the parts to carry but one person and he operate the mechanism, that the same relation of the 110 power of raising a given amount may be retained in case it is desired to form a large car at the bottom of the hanging frame E to carry passengers or freight, and that any 115 suitably constructed and operated engine may be employed, which may be located in such car to provide the required power necessary to drive the propeller-wheel.

I desire it understood that I do not desire 120 to limit myself to the exact details of construction shown, as these may be readily varied without departing from the broad principle of my invention. Neither do I show or confine myself to any particular construction 125 of the propeller-wheel, as such wheel may also be varied according to the power which may be required on differently constructed and weighted balloon-frames made according to my invention.

It is obvious that the propeller-frame and 130 the balloon-frame A to have the required strength should be suitably braced by means of suitable strut-braces 25 35, as shown.

Having thus described my invention, what

I claim, and desire to secure by Letters Patent, is—

1. An air-ship composed of a balloon-frame A, provided with the bag N on its upper face, 5 a propeller-wheel D, journaled thereon at one end, a depending cage or frame E, pivotally connected at its upper end to the balloon-frame, a crank-shaft journaled in the lower end of the cage, means for operating said 10 crank, as shown, intermediate gearing devices between said crank-shaft and the propeller-shaft, a guide-rope P, secured at its ends to the opposite ends of the frame A and passed over a guide near the lower end of the cage, 15 substantially as and for the purpose described.
2. The combination, with the balloon-frame A, provided with the members a' a', the shaft c, journaled in inner end of one of said members, the coincident end of the opposite members 20 provided with an apertured hub, a transverse brace or member formed with a depending bracket provided with an apertured hub, the shaft c' journaled in said hubs, provided at its inner end with a bevel-gear L, and the 25 shaft B, journaled between the members a' a', provided with a bevel-gear M at its inner end meshing with the gear L and a propeller-wheel at its outer end, of the depending frame or cage E, consisting of the bars e e, having 30 forked upper ends, one of said bars hung on the shaft c, the opposite bar hung on the
- apertured hubs, the lower end of said cage provided with a platform, foot-levers pivoted thereon, a crank-shaft G mounted on said bars, pitmen H, connecting said shaft G and 35 the foot-levers, said shaft G provided with crank-handles, a chain-belt connection between said shafts G and c', and a connection between the frame A and the lower end of the cage, whereby the said frame may be 40 swung to a vertical position, substantially as and for the purpose described.
3. The combination, with the balloon-frame A, provided with a propeller-wheel and a 45 depending dolphin-stick Q, of the frame or cage pivotally hung to said frame A, intermediate gear mechanism between said propeller-wheel and the cage E, means for operating said gear mechanism mounted on said frame or cage E, a pulley mounted on the 50 lower portion of said frame E, and the guide-rope secured to the rear end of the frame A, passed over the pulley 80, secured to the lower end of the dolphin-stick, its free end connected to the front end of the frame A, all 55 arranged substantially as and for the purpose described.
